UNITED STATES PATENT OFFICE.

ENOS B. HIATT, OF PALISADE, COLORADO.

RING PACKING LID.

Application filed October 13, 1925. Serial No. 62,278.

This invention relates to a ring packing lid and has relation more particularly to a device of this kind designed for use in the packing of fruit and the like whereby a completed pack is provided with an attractive top layer to assure an effective display of the packed contents and which at the same time permits stacking of the packs without injury to the contents.

10 Another object of the invention is to provide a packing ring lid especially designed and adapted for use in connection with my invention as disclosed in my Patent No. 1,573,341 dated February 16, 1926, the present device constituting an improvement on the ring packing lid embodied in such prior application.

15 The invention consists in the details of construction and in the combination and arrangement of the several parts of my improved ring packing lid whereby certain important advantages are attained and the device rendered simpler, less expensive and otherwise more convenient and advantageous for use, as will be hereinafter more fully set forth.

The novel features of my invention will hereinafter be definitely claimed.

20 In order that my invention may be the better understood, I will now proceed to describe the same with reference to the accompanying drawings, wherein:—

25 Figure 1 is a view partly in section and partly in elevation illustrating a pack produced with the use of my improved lid:

30 Figure 2 is a view partly in elevation and partly in section illustrating my improved lid in use and denoting the manner of such use, the container proper being diagrammatically indicated by broken lines;

35 Figure 3 is a view partly in section and partly in elevation illustrating another step in packing embodying the use of my improved lid;

40 Figure 4 is a view in top plan of the lid as disclosed in Figures 2 and 3 unapplied;

45 Figure 5 is a transverse sectional view taken through a slightly modified form of lid;

50 Figure 6 is a sectional view taken through a still further modified form of lid;

55 Figure 7 is a sectional view illustrating another embodiment of the invention.

As disclosed in the accompanying drawings, the lid or form L comprises the two superimposed plates 1 and 2, one of said

plates having its outer surface concave and provided at a predetermined point inwardly of its margin with an outstanding annular shoulder 3. The plate 1 inwardly of the shoulder 3 is provided with a series of angularly disposed concentric grooves or corrugations 4 in which the fruit or the like, such as apples, peaches, oranges, etc., are laid.

60 In Figure 4, the corrugations are three in number resulting in a central upstanding protuberance 5 whereby the desired arrangement of the fruit is assured and is adapted for comparatively large fruit, 70 while the lid or form L', as illustrated in Figure 5, is for a different size of fruit and is provided at its center with a depression 6 in lieu of the protuberance 5 and in which depression an apple or other fruit is adapted to be positioned. In Figure 6, the corrugations 4' are four in number for use with smaller fruit. These various forms of lids or forms are illustrated in the accompanying drawings to clearly establish the fact 80 that I do not wish to be understood as limiting myself to any particular number of corrugations as this will depend upon the requirements of practice and it will also be understood that if desired the outer concave 85 face of the plate 1 may be smooth or unobstructed.

86 The marginal portion of the plate 1 outwardly of the shoulder 3 is returned and clamped or otherwise effectively engaged 90 with an outstanding marginal flange 7 defining the plate 2, said plate 2 being substantially pan like in form with its central portion raised, as at 8, for substantial contact with the central or lower portion of the 95 plate 1 to effectively reinforce the same and particularly when the lid or form L is in use.

When my improved lid or form is employed in connection with a packing structure as particularly disclosed in my Patent No. 1,573,341 hereinbefore referred to, the lid or form L is preferably positioned on a slight incline toward the packer with the concave face of the plate 1 outwardly disposed. A layer of fruit is placed within the corrugations 4 whereupon the liner 9 positioned within a shell 10 is placed upon the lid or form L and substantially snugly receiving the shoulder 3 whereby the assembled liner 9 and shell 10 are effectively maintained in applied position upon the lid or

form. The liner 9 is formed of cardboard or other kindred material to provide a substantially weak wall liner while the shell 10 is of sheet metal or other material affording a substantially fixed formation.

The assembled liner and shell are then filled with fruit and the flange 7 engaged by the hands of the packer from below so that the completed assembly may be jarred 10 to cause the fruit or the like to settle. The shell 10 is then removed leaving the liner 9 holding the contents in proper shape. An inverted shipping basket or container C is then placed over the liner and pressed down 15 firmly. The lid or form L and applied basket are held firmly together and the basket or container turned right side up, after which the lid or form L is removed and the shipping lid S applied.

20 The lid or form L has a circular cavity adapted to receive a layer of fruit, the perimeter of the cavity being defined by an upwardly extending wall or shoulder as at 3' for contact with the periphery of the layer of fruit arranged upon the form to maintain the layer in proper position and to facilitate the application of the liner and shell or kindred retaining member, an outer circular guide wall 3 is provided immediately 25 outside of and paralleling the defining wall and over which the fruit retaining member extends when placed upon the form.

My improved lid or form L, however, is not limited to use in connection with the 30 packing structure hereinbefore referred to, as it is possible to directly apply upon the lid or form L from above the basket or container C with the shoulder 3 extending upwardly within said basket or container 40 when the basket or container is employed without the use of the shell or liner, it is preferred that initially the bottom of the basket be removed so that upon completing the filling of the basket, the bottom can be 45 applied and then the basket and lid or form inverted, after which the lid or form L will be removed and the ordinary basket or container lid or form or cover applied.

In the embodiment of my invention as 50 illustrated in Figure 7, the concave surface a of the lid or form L" is smooth and unobstructed and such lid or form L" is solid in construction, it being made of wood, fibre or any other desired material.

55 From the foregoing description it is

thought to be obvious that a ring packing lid constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:—

1. A ring packing form for use in connection with a fruit retaining member, said form being provided with a circular cavity for the reception of a layer of fruit, the cavity having a circular defining wall which is 75 adapted to contact with the periphery of the layer, the form being further provided with a circular guide wall over which the fruit retaining member extends when placed upon the form, the circular guide wall being located immediately outside of and paralleling the defining wall.

2. A ring packing form for use in connection with a fruit retaining member, said form being provided with a circular cavity 85 for the reception of a layer of fruit, a series of concentric grooves formed in the cavity to insure concentric arrangement of the fruit, the outermost groove having a circular defining wall which is adapted to contact 90 with the periphery of the layer, the form being further provided with a circular guide wall over which the fruit retaining member extends when placed upon the form, the circular guide wall being located immediately 95 outside of and paralleling the defining wall.

3. As a new article of manufacture, a ring packing lid comprising two superimposed plates having their marginal portions connected, one of said plates having its outer face concave, the second plate having its central part in contact with the low point of said concave to strengthen said first named plate, the first named plate adjacent its periphery but spaced therefrom being provided with an outwardly facing shoulder extending therearound.

In testimony whereof I hereunto affix my signature.

ENOS B. HIATT.
